HOSPITAL WARD UNIT

Gerardus Wilhelmus Maria Arts, Eindhoven, Netherlands, assignor to U.S. Philips Corporation

Filed Feb. 24, 1970, Ser. No. 21,596

Claims priority, application Switzerland Aug. 27, 1969

Term of patent 14 years

Int. Cl. D24—01; D26—05
U.S. Cl. D83—1

FIG. 1 is a perspective view of the hospital ward unit, showing my new design;

FIG. 2 is a front elevational view thereof;

FIG. 3 is a rear elevational view thereof;

FIG. 4 is a side elevational view thereof;

FIG. 5 is an elevational view of the opposite side thereof;

FIG. 6 is a top plan view thereof;

FIG. 7 is a bottom plan view thereof.

I claim:

The ornamental design for a hospital ward unit, as shown.
